Patented Jan. 10, 1922.

UNITED STATES PATENT OFFICE.

GEORGE L. MASON, OF WAREHOUSE POINT, CONNECTICUT, ASSIGNOR TO THE J. R. MONTGOMERY COMPANY, OF WINDSOR LOCKS, CONNECTICUT, A CORPORATION.

SERVING SPINDLE.

1,403,181.

Specification of Letters Patent. Patented Jan. 10, 1922.

Application filed September 1, 1920. Serial No. 407,480.

To all whom it may concern:

Be it known that I, GEORGE L. MASON, a citizen of the United States, and resident of Warehouse Point, county of Hartford, State 5 of Connecticut, have invented certain new and useful Improvements in Serving Spindles, of which the following is a specification.

This invention relates generally to serving 10 spindles or heads for winding or wrapping one strand about a second strand or core of the same or a different material; for instance, a metal ribbon about a strand of cotton or other pliable fab'r'c.

The object of the invention is to provide 15 a device of this sort which is efficient and reliable in operation, and particularly in that the covering strand or metal ribbon is uniformly and evenly wound about the core.

20 In the accompanying drawing, I have illustrated my improvements applied to a serving spindle such as is illustrated and described in application Serial No. 331,816, filed by myself and George M. Montgomery, but it 25 is evident that my improvements may be used on serving spindles of other types. It is to be understood that the present invention is by way of illustration only and that the construction may be variously modified without 30 departing from the spirit of the invention.

In said drawing:

Fig. 1 is an elevational view of the serving spindle, a portion thereof in longitudinal section, and

35 Fig. 2 is an enlarged sectional view of the forward end of the device.

Before describing the improvements of the present invention, the general arrangement of the serving spindle here selected for illustrative purposes, and the particular structure of which forms no part of the present invention, will be described. *a* is a spool containing the covering strand or metal ribbon and carried by a sleeve *b* surrounding and in 40 frictional engagement with, so as to be rotated by, a spindle *c* journalled on a stationary tubular member *d* through which is drawn the core strand *e* as by a driven spool *s*. Extending through this member and 45 projecting beyond the forward end thereof is a tapering needle *f* mounted for longitudinal adjustment. Fixed to the spindle is a flier *g* having a pivoted thread guide *h* through the eye of which the metal ribbon is 50 threaded. The forward end of the sleeve *b*

is held in frictional engagement with a shoulder *i* by a tensioning device of which the thread guide *h* forms a part, as described in the said Montgomery & Mason application.

It will be understood by those familiar with the art that, in operation, the flier will lay the metal ribbon, designated by the letter *k*, in a spiral manner upon the core thread *e*. The object of the needle is to cause the metal 65 ribbon to be wound loosely on the core, that is, to make the loops or convolutions of the ribbon of greater diameter than that of the core so that the composite thread can be flattened out by passing it through rolls, if 70 so desired. By adjusting the needle longitudinally, the diameter of the loops or convolutions of the metal strip may be regulated.

Heretofore, in constructions of this general type, the metal ribbon has been entirely free 75 and unsupported between the thread guide of the flier and the point at which it is wound onto the core, with the result that the winding point, that is the point at which the metal strip is laid on the core, varies or 80 moves and frequently this winding point will advance forwardly beyond the needle. This faulty operation necessitated the constant attention of an operator, the work turned out was un-uniform and faulty and 85 the device could be operated at only relatively low speeds.

Referring now to the improvement of the present invention and with which the above and other objections incident to the past 90 practice are overcome, the numeral 10 denotes, what may be termed for convenience, a head (most clearly shown in Fig. 2) which is so arranged as to form a bridge or a guide as it were for the metal ribbon between the 95 thread guide of the flier and the winding point. This head 10 may have a threaded shank 11 which takes into the forward end of the tubular member *d* and the rear face of the head may constitute the shoulder *i* 100 above referred to. The forward end of the head is recessed as at 12. The shank has a small centrally located opening 13 through which the needle *f* projects and an eccentrically positioned opening 14 through which 105 the core strand *e* is threaded. If desired, the needle and core may both pass through the centrally located opening. It will be seen that by recessing the head a ring like portion or annulus is provided. The ar- 110

arrangement of the parts is such that the thread guide of the flier is rearwardly of the forward end of the head 10 so that during the winding operation the metal ribbon 5 is drawn across the shoulder or forward face of the annulus. I have found that with this arrangement the metal strip, after it engages the annulus, will be directed at substantially right angles to the core strand and needle and 10 the point at which the metal ribbon is wound on the core and needle is thereby maintained constant. The results are the device operates with great uniformity insuring that the metal strip is evenly and smoothly laid 15 onto the core and the attention of an operator may be dispensed with except for the purpose of replenishing the spools, and furthermore, the device may be run at much higher speeds than has heretofore been 20 possible.

I claim as my invention:—

1. In a device of the character described, a flier for laying a covering strand onto a core strand, and a stationary bridge between 25 said flier and the winding point and over which the covering strand is drawn.
2. In a device of the character described, a needle along which a core strand is adapted to be drawn, a flier for winding a covering strand on said needle and the core strand, and a bridge having an edge spaced from said needle and over which edge the covering strand is drawn.
3. In a device of the character described, 35 a flier for laying a covering strand onto a core strand, and an annulus through which

the core strand is drawn, said annulus supporting said covering strand at a point between said flier and the winding point.

4. In a device of the character described, 40 a needle along which a core strand is adapted to be drawn, a flier for laying a covering strand onto the core strand and said needle, and an annulus encircling the needle and core strand but spaced therefrom and arranged to support the covering strand at a point between the flier and the winding point.

5. In a device of the character described, 50 a needle, means for drawing a core strand longitudinally thereof, a flier including a thread guide for winding a covering strand on the core strand and needle, and a ring like member encircling the core strand and needle and positioned forwardly of the 55 plane in which said thread guide rotates so that said covering strand will be drawn over the edge of said member and deflected thereby toward the core strand.

6. In a device of the character described, 60 a member forming a passage for a core strand, a needle extending through said passage, a flier including a thread guide and rotatably mounted on said tubular member, and a circular head on the forward end of 65 said member and encircling said needle and core strand, the forward end of said head being recessed providing an edge positioned forwardly of the thread guide over which the covering strand is drawn.

GEORGE L. MASON.
